UNITED STATES PATENT OFFICE.

WILLIAM R. JOHNSTON, OF CHICAGO, ILLINOIS, ASSIGNOR TO WM. R. JOHNSTON MFG. CO., OF CHICAGO, ILLINOIS, A CORPORATION OF ILLINOIS.

DESIGN FOR A CURTAIN-WINDOW FOR VEHICLES.

58,763.

Specification for Design.

Patented Aug. 30, 1921.

Application filed July 23, 1920. Serial No. 398,587. Term of patent 7 years.

To all whom it may concern:

Be it known that I, WILLIAM R. JOHNSTON, a citizen of the United States, residing at Chicago, in the county of Cook and State of Illinois, have invented a new, original, and ornamental Design for a Curtain-Window for Vehicles, of which the following is a specification, reference being had to the accompanying drawing, forming a part thereof.

In the drawing: The figure is a face view

of a curtain window for vehicles showing the new design.

The design is characterized by a curtain 4, transparent plate 2, having a beveled margin 3, and a round bead 5 around said margin, the plate, beveled edge and bead being of the shape shown.

I claim:

The ornamental design for a curtain window for vehicles as described and shown.

WILLIAM R. JOHNSTON.
